UNITED STATES PATENT OFFICE

2,289,257

COMPUTING DEVICE

Albert E. Fiala, Chicago, Ill.

Application March 9, 1939, Serial No. 260,809

2 Claims. (Cl. 235—79.5)

The invention relates to computing devices wherein a plurality of rotary indicators are actuated to compute certain data.

It is an object of the invention to provide means for causing rotation of all the rotary indicators in unison, and relative motion between some indicators and others.

A further object constitutes the provision of means extraneous to the device for actuating the rotary indicators.

Another object constitutes the provision of means co-axial with the rotary indicators for driving the indicators in unison, and eccentric means for actuating certain indicators to produce relative motion with respect to others of said indicators.

It is also an object of the invention to provide certain features of construction and arrangement of parts tending to enhance the efficiency and utility of a device of the character specified.

It is a still further object to provide a series of endless belts constituting indicators, there being means for actuating said belts in unison and relatively to each other respectively.

With these and other equally important objects in view, which will become apparent from a perusal of the invention, the latter comprises the means described in the following specification, particularly pointed out in the claims forming a part thereof, and illustrated in the accompanying drawing, in which:

Fig. 1 is a front view of the device constructed in accordance with the invention.

Fig. 2 is a side view thereof.

Fig. 3 is a section on the line 3—3 of Fig. 2.

Fig. 4 is a section on the line 4—4 of Fig. 3, and

Fig. 5 is a side view of a modification.

Referring to the several views in the drawing, 10 designates a base to which are secured by screen 11 bearing walls 12, having an aperture for the reception of a hollow shaft 13.

Wheels 14 and 15, constituting rotary indicators, are mounted in spaced relation on said shaft and in press fit relation therewith so that, upon rotation of the shaft, wheels 14 and 15 will rotate therewith.

The periphery 16 of each wheel is surrounded by a removable band 17 on which indicia, graduations or other marks 18 are provided, necessary or useful for the computations to be made.

Intermediate to the wheels 14 and 15 is a wheel 19, loosely mounted on the shaft, but also provided with a band 17 having graduations 18.

The hub 20 of the wheel 19 is counter-sunk, 55

as at 21, to receive therein an internal gear 22, with which meshes a pinion 23 on a solid shaft 24, mounted eccentrically in the hollow shaft and supported in end plates 25, forming closures for the hollow shaft.

A slot 26, in the hollow shaft, provides clearance for the pinion 23.

The right end, as viewed in Fig. 1 of shaft 13, extends beyond the side wall 12, and carries a hand wheel 27 for actuation of the hollow shaft, whereas the shaft 24 extends beyond the right end wall 25 and is provided with a knob 28 for rotation of the solid shaft.

The manipulation of the device is as follows:

15 Upon rotation of the hollow shaft, the wheels 14 and 15 rotate therewith. Likewise, the wheel 19 is caused to rotate, as it is coupled with the shaft by the engagement of the teeth of gears 22 and 23.

20 When it is desired to cause relative motion between the wheel 19 and the wheels 14 and 15, then the knob 28 is turned while the handle wheel 27 is held against rotation, whereupon the wheel 19 alone turns.

25 It is, of course, understood that any one of the wheels may be arranged to have rotation independent of the others, nor is the number of wheels limited, but may be increased to any number desired.

30 The particular graduation employed may vary in accordance with special requirements, and the graduations are shown merely by way of example.

To this end, the bands 17 may be replaced by other bands having the desired graduations.

35 Where considerable space is required for the accommodation of graduations, the modification shown in Fig. 5 may be used.

Here a base 20 is employed, from which up-stand spaced pairs of bearing walls 31 and 32.

40 A shaft 33 carries a plurality of wheels 34, around which are trained belts 35 which encompass wheels 36. The construction of the wheels 36 is identical with those in the first described embodiment, there being a hand wheel 37 and a knob 38, for respectively rotating the wheels in unison, and one of the wheels independently of the others.

While the drawing shows preferred embodiments of the invention, numerous changes and alterations may be made without departing from the spirit of the invention.

I, therefore, do not limit myself to the details of construction and arrangement of parts, as shown, but claim my invention as broadly as the state of the art permits.

I claim:

1. A device of the character described comprising a support, a tubular shaft having an aperture in the cylindrical surface thereof and rotatably mounted in the support, said tubular shaft being closed at the ends, a plurality of indicators fast on said shaft for rotation therewith, another indicator rotatably mounted on said shaft and provided with a gear, and a solid shaft extending through the closed ends of said tubular shaft in eccentric relation thereto and provided with a pinion adapted to engage said gear through the aperture of said tubular shaft. 10

2. In a computing device, a hollow shaft having an aperture in the cylindrical surface thereof and closed at the ends, a plurality of drums fast on said shaft, a drum having an internal gear loose on said shaft, and a second shaft having a pinion eccentrically arranged in said hollow shaft and journaled in the closed ends of said hollow shaft, the pinion extending through the aperture in the hollow shaft to mesh with the internal gear of said loose drum to positively drive the latter. 5

ALBERT E. FIALA.
